COMPOSITE STAINLESS-STEEL PANIC EXIT CASE
Homer A. Eichacker and John R. Foster, Indianapolis,
Ind., assignors to Vonnegut Hardware Company, Indianapolis, Ind., a corporation of Indiana

Filed June 25, 1958, Ser. No. 744,450
5 Claims. (Cl. 292—92)

The present invention relates to an improved construction of a case for a panic exit assembly and more particularly relates to a composite, partially stainless steel, construction for a panic exit case which makes possible the use of stainless steel as the only visible material in a panic exit assembly.

In the past, panic exit assemblies have been manufactured from brass, bronze and similar materials. It is desirable that such assemblies be formed, at least outwardly, of stainless steel because of its non-tarnishing and pleasing appearance; however, the cases of the panic exit assembly (the members which are fixed to the door and which pivotally carry the panic bar) are so formed internally and externally that they are prohibitively expensive to cast and commercially impracticable to forge out of stainless steel.

It is, therefore, an object of the present invention to provide a construction which makes possible forming all of the external visible surfaces of a case for a panic exit assembly out of stainless steel in an inexpensive and easy manner.

Still further objects of the invention will appear as the description proceeds.

To the accomplishment of the above and related objects, our invention may be embodied in the form illustrated in the accompanying drawings, attention being called to the fact, however, that the drawings are illustrative only, and that change may be made in the specific construction illustrated and described, so long as the scope of the appended claims is not violated.

FIG. 1 is a side elevation of a panic exit assembly embodying the present invention, shown rotated counter-clockwise 90 degrees from the position in which it is normally attached to a door and having certain parts thereof broken away to show certain internal structure;

FIG. 2 is a bottom view of portions of the panic exit assembly of FIG. 1, having portions thereof broken away to show certain internal features of the assembly;

FIG. 3 is a section looking in the direction of the arrows and along the line 3—3 of FIG. 1, and showing certain internal features of a latch assembly forming a portion of the panic exit assembly; and

FIG. 4 is a section looking in the direction of the arrows and along the line 4—4 of FIG. 1 and showing certain features of a means for attaching the panic exit assembly to a door.

Referring now to the drawings, we have illustrated a panic exit assembly, indicated generally at 10, which comprises a panic bar 11 extending in a direction perpendicular to the plane of the drawing and fixed at one end to a rocker arm 12 which is pivotally mounted upon a case, indicated generally by the numeral 16. The other end of the panic bar 11 is fixed to another rocker arm (not shown) similar to the rocker arm 12, which other rocker arm is also pivotally mounted upon a case (not shown) generally similar to the case 16. The rocker arm 12 extends into the case 16 in such a manner that, when the rocker arm 12 is pivoted clockwise as viewed in FIG. 1, means are actuated to retract a latch bolt 17, forming a portion of a latch assembly, indicated generally at 15, and mounted within the case 16.

The other, not shown, case of the panic exit assembly conventionally mounts and houses a relatively powerful

2

spring means for yieldably holding the panic bar 11 and associated rocker arms in a raised, counter-clockwise position, as viewed in FIG. 1, whereby the latch bolt 17 is allowed to remain in a protruding position. During the following description of the invention, it will become apparent that the invention can be used in either of the cases of a panic exit assembly no matter whether the case provides a housing and mounting for a latch assembly, for a relatively powerful spring means for holding the panic bar in a raised position, for both of these, for other panic exit operating mechanism, or for any combination of the above.

In the past, the case 16 has been formed in such a manner that a bracket 22 is integral therewith and so that the internal surfaces of the case 16 provide a mounting for the latch assembly 15. As can be seen from the drawings, the bracket 22 is relatively thick and heavy and the internal construction of the case 16 must also be relatively thick and heavy with various ridges and bumps so as to provide a suitable mounting for the latch assembly 15. In our invention, the case 16 is formed of three separable pieces, namely, the bracket 22, a shell 21 and a chassis, indicated generally by the numeral 20. The shell 21, which is generally of elongated cup-shape, has a thin, relatively constant thickness throughout and thus is relatively easy to manufacture from stainless steel, preferably by a drawing operation. The bracket 22, even though it is thick and heavy, is of a compact shape and therefore is also relatively easily manufactured from stainless steel, either by casting or by forging. The chassis 20 which contains a plurality of ridges and other projections for mounting of the latch assembly 15 is not visible to the eye and therefore may be formed of brass or any other suitable, easily cast or forged material. The elongated cup-shaped shell 21 has, opposite the principal opening 23 of the cup-shaped shell, a base wall 24, which has fixed thereagainst, in a manner to be explained below, the bracket 22. A side wall 18 extends completely around the shell 21 and has an edge 27 which forms a boundary for the opening 23 and is normally fixed in engagement with a door upon which the panic exit assembly is mounted.

The chassis 20 is fixed within the shell 21 by means of a pair of hollow screws, indicated generally by the numerals 25—25, having inwardly and outwardly tapering heads 26—26. The hollow portion of each screw is formed for receiving a hexagonal wrench, which may be operatively engaged within the portion 28 of the hollow portion of the particular screw 25, for turning the screw so as to attach or release the chassis 20 to or from the shell 21. It will be apparent that the hollow portion of each of the screws 25 is also formed so as to receive another tapered headed screw 29 for attaching the panic exit assembly to a door. It will be noted from the drawings that the inward tapering portion of the head of the screw 25 is shaped in such a manner as to receive the tapered headed screw 29 which may be composed of stainless steel as are the other visible portions of the present panic exit assembly.

The bracket 22 has a pair of generally cylindrical projections 34—34 (one shown in FIG. 1), each of which has a suitable threaded bore therein for reception of one of a pair of screws 33—33. The screws 33—33, which extend through bores 44—44 in the chassis 20, hold the bracket 22 against the base wall 24 of the shell 21 by fixing the projections 34—34 within suitable openings in the shell 21 and within counterbores 48—48 in the chassis 20.

In the illustrated embodiment of our invention, an open centered, generally rectangular latch retractor member 30 is slidably received between four elongated ridges 31—31 integral with, and projecting from, the chassis

20. The latch bolt 17 is pivotally mounted upon a trunnion pin 35 so as to normally protrude from an opening 19 in the side wall 18 of the shell 21 but may be retracted within the shell 21 by means of a projecting hook-like portion 36 of the latch retractor member 30 which engages a pin 37 fixed within the latch bolt 17. The latch bolt 17 is urged to its normal protruding position by means of a pair of springs 42—42 which are received between the latch retractor member 30 and the terminal heads 41—41 of a pair of parallel pins 40—40 and about the pins 40 which are received in suitable bores within the latch retractor member 30. The springs 42 force against the heads of their respective pins 40 causing the heads of the pins to force against a surface 43 of the chassis 20 and to cause the latch retractor member 30 to be moved rightwardly as viewed in FIG. 3.

A cam member 45 is pivotally mounted upon a post 46 integral with and extending from the chassis 20. The cam member 45 may be actuated by a finger 47 integral with and projecting from the rocker arm 12, which is pivotally mounted upon trunnion means 50 fixed to the bracket 22. When the cam member is so actuated, it forces against a camming surface 51 on the latch retractor member 30 to move the latch retractor member 30 leftwardly, as viewed in FIG. 3, thus retracting the latch bolt 17. The rocker arm 12 extends through an opening 53 in the bracket 22 and through an opening 52 in the base wall 24 of the cup-shaped shell 21, the openings 52 and 53 being in registry with one another.

A cover plate 55, only partially shown in FIG. 2, and which may provide a mount for means (not shown) operated from the opposite side of the door from the side upon which the panic exit assembly is mounted for independently actuating the latch retractor member 30 to retract the latch 17, is fixed to the chassis 20 by means of a plurality of screws 56 threadedly received within threaded bores 57—57 in ridges 58—58 forming a part of the chassis 20. A screw 60 having a hollow hexagonal shaped socket 61 for reception of a wrench for turning the screw, functions as a dog for holding the rocker arm 12 in such a position that the latch bolt 17 is held retracted, if desired. The hollow hexagonal portion 61 of the screw 60 is accessible through a cylindrical opening 62 in the side wall 18 of the shell 21.

We claim as our invention:

1. In a panic exit assembly, a stainless steel, cup-shaped shell, a chassis formed for mounting a latch assembly thereon, said chassis having a plurality of threaded apertures therethrough, an equal plurality of hollow screws extending through said shell and into said threaded apertures and fixing said chassis within said shell, the hollow portions of said plurality of screws being formed for reception of a means for turning said screws and also formed for reception of a further equal plurality of screws for fixing the panic exit assembly to a door.

2. A panic exit assembly comprising a stainless steel, cup-shaped shell of relatively constant thickness, said shell having a base wall and a side wall and having an opening in its base wall and an opening in its side wall, a chassis formed for mounting a latch assembly thereon, said chassis being fixed within said shell, a latch assembly, including a latch bolt, mounted upon said chassis, said latch bolt normally protruding through the opening in the side wall of said shell, a stainless steel bracket fixed to the outer surface of the base wall of said shell and having an opening registering with the opening in the base wall of said shell, and a rocker arm pivotally mounted upon said bracket and extending through the opening in said bracket and the opening in said base wall for actuating said latch assembly to retract its latch bolt.

3. A panic exit assembly comprising a stainless steel, cup-shaped shell of relatively constant thickness, said

cup-shaped shell having a base wall and a side wall and having an opening in its base wall and an opening in its side wall, a chassis formed for mounting a latch assembly thereon, said chassis having a plurality of threaded apertures therethrough, an equal plurality of hollow screws extending through said shell and into said threaded apertures and fixing said chassis within and to said shell, the hollow portions of said plurality of screws being formed for reception of a means for turning said screws and also formed for reception of a further equal plurality of screws for fixing the panic exit assembly to a door, a latch assembly mounted upon said chassis and having a latch bolt normally protruding through the opening in the side of said shell, a stainless steel bracket fixed to the outer surface of the base wall of said shell and having an opening registering with the opening in said base wall of said shell, and a rocker arm pivotally mounted upon said bracket and extending through the opening in said bracket and the opening in said base wall for actuating said latch assembly to retract its latch bolt.

4. A panic exit assembly comprising a stainless steel, cup-shaped shell of substantially constant thickness, said shell having a base wall provided with port means and a side wall having an opening therethrough, a separate chassis received in said shell, said chassis being formed on one surface with a socket arranged, when said chassis is so received, to register with a portion of said port means and said chassis being further formed to receive and support a latch assembly including a latch retractor member supported from the opposite surface of said chassis, a latch bolt supported from said chassis, normally protruding through said side wall opening of said shell and having an operative connection with said latch retractor member, a stainless steel bracket formed to provide a surface conformably engageable with the external surface of said shell wall and having stud means penetrating said port means and seated in said socket, screw means penetrating said chassis and threadedly engaging said stud means to secure said bracket in place on said shell, said bracket further being formed with an opening therethrough registering with a portion of said port means and said bracket further providing trunnion mounting means, and a rocker arm pivotally supported from said trunnion mounting means and having a portion extending through said bracket opening and said port means into operative engagement with said latch retractor member.

5. In a panic exit assembly, a stainless steel, cup-shaped shell of substantially constant thickness, a chassis formed for mounting panic exit operating mechanism thereon, said shell being formed with a plurality of spaced openings therethrough and said chassis being provided with a plurality of threaded bores registering, respectively, with said openings when said chassis is received within said shell, a hollow, flare-headed screw for each such bore, each screw penetrating its opening, threadedly seating in its bore and being disposed with its flared head securely engaging the periphery of its opening to secure said chassis in place in said shell, and a further screw passing axially through each of said hollow screws to secure said assembly to a door.
